UNITED STATES PATENT OFFICE.

ROBERT E. HUNN, OF OAKLAND, CALIFORNIA.

LIFTER FOR MOLDED OBJECTS.

1,113,122.

Specification of Letters Patent.

Patented Oct. 6, 1914.

Application filed November 4, 1913. Serial No. 799,121.

To all whom it may concern:

Be it known that I, ROBERT E. HUNN, a citizen of the United States, residing at Oakland, in the county of Alameda and State of California, have invented new and useful Improvements in Lifters for Molded Objects, of which the following is a specification.

The object of the present invention is to provide an implement for rapidly and conveniently removing, from a mold in which it is formed, an article, having two parallel inwardly or oppositely inclined flanges, such as a glass tile like that shown in my application for Letters Patent, Serial No. 749,169 filed February 18th, 1913. The present method of removing such a tile is to remove the mold from the table on which it is supported, place above the tile a suitable support, invert the mold, by which inversion the tile is caused to rest on the support, remove the mold upwardly therefrom, and then remove the tile from the support on to a cooling plate. This operation necessitates the employment of two men, and occupies much time.

In the accompanying drawing, Figure 1 is a broken plan view showing the tile in the mold and the implement in position ready to be applied thereto; Fig. 2 is an enlarged similar view showing the implement applied to the tile and clamping its flanges; Fig. 3 is an enlarged cross sectional view on the line 3—3 of Fig. 2.

Referring to the drawing, 1 indicates a handle, a portion 2 of which is reduced in thickness. The handle is extended at the outer end of the reduced portion into a body 3 having a narrow longitudinal central portion 4 in line with the handle, and outwardly flaring terminal portions 5, 6, the terminal portion 5 being that by which the body extends from the handle. On the bottom of said extension or body 3 is a rectangular plate 7. Secured to, and extending from, the top of said terminal portion 5 almost at right angles to the handle are plates 9. On said terminal portion 6 and extending at right angles to the handle is secured a plate 10, and secured to the outer ends of the plates 9 and 10 and beneath the same are two parallel bars 11, having undercut inner edges. Movable on said plate 7, and between said plate 7 and plates 9 and 10 are two blocks 13, 14, of which the outer

edges are normally parallel with the bars 11, and the inner edges normally extend in like directions with the adjacent edges of the body 3. To move said movable blocks there is provided a lever 16 pivoted, as shown at 17, upon the terminal portion 5, and arranged to move over the reduced portion of the handle 1. Extending from one end of said lever to one side thereof is a curved arm 18 pivoted, as shown at 19, to the block 13. On the same end as the arm 18, but on the opposite side, there extends a short arm 21. Upper and lower plates 22, 23 are secured upon said arms 18 and 21 and lever 16. A pivot 24 extends through said short arm 21 and plates 22, 23 and through two plates 26, secured on opposite sides of, and extending from, a lever 27, pivoted on a stud or post 28 secured to, and extending upwardly from, the plate 7 through a slot 29 in the block 14, the outer end of said lever 27 being pivoted, as shown at 30, to said block 14. The outer straight edges of said blocks 13 and 14 are beveled outwardly and downwardly or in planes parallel with the inner undercut edges of the bars 11. A spring 31 is secured to the lever 16 and bears against a stop 32 on the part 5, and a stop 33 on the handle limits the movement of said lever.

In use, the outer end of the plate 7 is placed on the outer end of the mold 34, so that the spaces between the bars 11 and the outer edges of the blocks 13, 14, are in alignment with the respective flanges 35 of the tile 36, and then the implement is moved longitudinally in the direction parallel with said flanges, so that said flanges are in said spaces. The lever 17 is then moved against the force of the spring 31, so as to be in registry with the handle, which movement causes both blocks 13, 14 to move outward, thus clamping the flanges of the tile respectively between the blocks 13, 14, and the bars 11. The glass tile can then be raised from the mold by means of said flanges. When the tile has been placed upon a cooling plate, pressure is withdrawn from the lever 16, whereupon the blocks are retracted from the bars by the action of the spring 31, and the implement can be slid backward from the tile.

For the reason that the blocks 13, 14 are moved toward the bars 11 with considerable force, any irregularities accidentally

formed in the flanges in the process of molding are pressed out by said bars and blocks.

It will be seen that with this implement 5 one man can do the same work as two men and in a small fraction of the time.

I claim:—

1. In an implement of the character described, the combination of a body, a handle therefor, side bars spaced from the body, supporting means for said side bars secured to the body, blocks movable on said body to and from the respective side bars, and having beveled outer edges, a lever movable in 10 proximity to said handle, and operative connections between said lever and blocks whereby, with the movement of the lever in one direction, both of said blocks move outwardly, and, with the movement in the other 15 direction, both blocks move inwardly.

2. In an implement of the character described, the combination of a body, a handle therefor, side bars spaced from the body, having undercut inner edges, blocks movable 20 on said body to and from the respective side bars, and having beveled outer edges, a lever movable in proximity to said handle, and operative connections between said lever and blocks whereby, with the 25 movement of the lever in one direction, both of said blocks move outwardly, and, with the movement in the other direction, both blocks move inwardly.

3. In an implement of the character described, the combination of a body, a handle therefor, side bars spaced from the body, supporting means for said side bars secured to the body, blocks movable on said body to and from the respective side bars and 30 having beveled outer edges, a lever movable into alinement with said handle, a spring for returning said lever in the opposite direction, and operative connections between 35

said lever and blocks whereby, with the first-named movement of the lever, both of 40 said blocks move outwardly, and, with its opposite movement, both blocks move inwardly.

4. In an implement of the character described, the combination of a body, a handle therefor, side bars spaced from the body, supporting means for said side bars secured to the body, blocks movable on said body to and from the respective side bars and having beveled outer edges, a device 50 movable in opposite directions relatively to the said body, and operative connections between said device and block whereby, by the movement of the device in one direction, both of said blocks move outwardly, and by 55 its movement in the opposite direction both blocks move inwardly.

5. The combination of a body, a handle therefor, a plate secured to the under side of said body, parallel side bars, spaced from 60 said body, and having undercut inner edges, supports secured to the upper side of said body, to the under side of which supports the bars are secured, blocks having beveled outer edges, and movable upon said plate 65 and beneath said supports, a device movable on said body in opposite directions, and operative connections between said device and blocks whereby, by the movement of said device in one direction, said blocks are 70 both moved outwardly, and, by its movement in the opposite direction, said blocks are 75 both moved inwardly.

In testimony whereof I have hereunto set my hand in the presence of two subscribing 80 witnesses.

ROBERT E. HUNN.
